* cited by examiner

Primary Examiner—Caron D. Veynar*Assistant Examiner*—Ricky Pham(74) *Attorney, Agent, or Firm*—Renner, Kenner, Greive, Bobak, Taylor & Weber(57) **CLAIM**

The ornamental design for a safety shield for an ice shaver bin, as shown and described.

DESCRIPTION

FIG. 1 is a perspective view of a safety shield for an ice shaver bin showing our new design in the environment of an ice shaving and dispensing machine which is shown in phantom lines and which is not part of the claimed design; FIG. 2 is a perspective view of a safety shield for an ice shaver bin showing our new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
